UNITED STATES PATENT OFFICE.

J. HARRIS, JR., AND E. HARRIS, OF BOSTON, MASSACHUSETTS.

HAND-STAMP.

Specification of Letters Patent No. 18,308, dated July 24, 1855.

To all whom it may concern:

Be it known that we, JOSEPH HARRIS, Jr., and ELBRIDGE HARRIS, of Boston, county of Suffolk, and State of Massachusetts, have 5 invented a new and useful Improvement in Hand-Stamp Printing-Presses; and we do hereby declare that the following is a full and exact description thereof, reference being had to the accompanying drawings and 10 to the letters of reference marked thereon.

The nature of our invention consists in a new mode of hand stamp printing.

To enable others skilled in the art to make and use our invention we will proceed to 15 describe its construction and operation.

Figure 1 is a side elevation, Fig. 2 is a longitudinal section, Fig. 3 is a plan, Fig. 4 front view.

The letter A is a piston, which passes 20 through cylinder B and has at its end a die, marked C. The arms D D of the cylinder extend to the sides of the frame E, and become a fulcrum, by turning on their journals and boxes marked F F. The box being 25 stationary gives the whole when operated an oscillating motion for the purpose of inking the die, when passing over the ink roll G. The roll turns upon the journals and boxes H H, having a spring connected for 30 the purpose of allowing the ink roll to have an adjusting motion.

The letters J J are adjusters, being attached to the arms or fulcrum D D, and are

placed on both sides of the cylinder B and 35 near the sides of the frame E, and are operated by the same motion with the die, and comes in contact with the ink roll boxes H H for the purpose of adjusting the roll to meet the die to be inked.

The letter K is a bed plate, upon which 40 the article to be printed is placed before receiving an impression.

The distance through which the cylinder B is allowed to oscillate is regulated by 45 means of the checks L L and M M, which are attached to the frame E, the one above and the other below the journals F F, against which the adjusters J J come in contact at the limit of vibration.

The advantages this stamp has over others 50 is that it will perform the same amount of work better and quicker on account of its peculiar motion and new mode of inking, thereby saving labor, and is more compact and can be manufactured at less expense. 55

What we claim as new and desire to secure by Letters Patent, is—

The peculiar oscillating motion of the stamp, also the same in combination with the inking roll and its adjusters, for the purpose herein described. 60

JOSEPH HARRIS, JR.
ELBRIDGE HARRIS.
